SLIDING WINDOW

Frank McM. Sawyer, Miami, Fla.

Application September 23, 1944, Serial No. 555,524

8 Claims. (CL. 20—52)

1

The invention relates to a new and improved sliding window for dwellings and other buildings.

One object of the invention is to provide a comparatively simple and inexpensive construction in which all parts may be easily constructed.

Another object is to provide a novel construction which permits the slidable closure to slide into the space, provided by the usual furring strips, between the building wall and the inner wall (of lath and plaster, or wallboard) secured to said furring strips.

A further object is to make novel provision for so mounting the slidable closures that they may be easily installed after the building is practically completed, and may later be readily removed for cleaning or for replacing any which may be broken.

A still further object is to provide a novel construction in which each slidable closure consists of a pane of glass provided at its lower edge with a shoe to engage a guide rail, no sash being required.

Yet another object is to provide a slidable window which may be easily and tightly screened.

With the foregoing and minor objects in view, the invention resides in the novel subject matter hereinafter described and claimed, description being accomplished by reference to the accompanying drawings.

Figure 1 is an inner side elevation, partly broken away.

Fig. 2 is an outer side elevation with parts of the screen wire broken away.

Fig. 3 is an enlarged vertical section on line 3—3 of Fig. 1.

Fig. 4 is a fragmentary horizontal section on line 4—4 of Fig. 1.

Fig. 5 is a fragmentary vertical section on line 5—5 of Fig. 3.

Fig. 6 is an enlarged horizontal section on line 6—6 of Fig. 5.

Fig. 7 is a fragmentary perspective view showing more particularly the manner of inserting or removing one of the closure-abutting posts.

Fig. 8 is a detail vertical section on line 8—8 of Fig. 1 with the closures removed.

Fig. 9 is a fragmentary perspective view showing part of one of the slidable closures.

A preferred construction has been illustrated and will be specifically described, with the understanding, however, that within the scope of the invention as claimed, variations may be made.

The frame of the window embodies a sill structure 10, a crown structure 11, and stile structures 12. The sill structure 10 comprises an outer sill

2

13 and an inner sill or stool 14; the crown structure 11 includes an outer crown bar 15 and an inner crown bar 16, spaced apart; and each stile structure 12 includes an outer stile 17 and an inner stile 18, spaced apart.

Secured upon the inner sill or stool 14 is a lower rail 19 which extends snugly between the outer stiles 17 and the inner stiles 18. The end portions of this rail 19 project beyond the stile structures 12 to lie against the inner side of a building wall 20. Also secured upon the inner sill or stool 14 and secured against the rail 19, are an outer bar 21 and an inner bar 22, said outer bar 21 extending from one of the outer stiles 17 to the other, while said inner bar 22 extends from one of the inner stiles 18 to the other.

Secured between and in contact with the outer and inner crown bars 15 and 16, is an upper rail 23, the ends of which project beyond the stiles 20 to lie against the inner side of the wall 20. This rail 23 is shown projecting downwardly beyond the outer crown bar 15, and the outer side of its downwardly projecting portion lies against a bar 24 secured to the lower side of said outer crown bar 15, said bar 24 extending from one of the outer stiles 17 to the other.

Two intermediate rails 25 and 26 are shown, although there may be more than two, or only one, according to the size of the window. These rails 25 and 26 extend snugly between the outer stiles 17 and the inner stiles 18 and their ends project beyond the stiles to lie against the inner side of the wall 20. Outer bars 27 and 28 are secured against the outer sides of the rails 25 and 26, respectively, and extend from one of the outer stiles 17 to the other; and inner bars 29 and 30 are secured against the inner sides of said rails 25 and 26 and extend from one of the inner stiles 18 to the other.

One central post 31 extends from the bar 24 to the bar 27 and is secured thereto; a second central post 32 extends from said bar 27 to bar 28 and is secured to them; and a third central post 33 extends from said bar 28 to the bar 21 and is secured to these bars.

Outer stop strips 34 are secured to the inner sides of the outer stiles 17, and inner stop strips 35 are secured to the inner stiles 18, said stop strips 34 extending between the bars 24, 27, 28 and 21, while said stop strips 35 extend between the bars 16, 29, 30 and 22. The outer faces of all of the elements 24, 27, 28, 21, 31, 32, 33 and 34 are in a single plane in order that screen wire 36 may be secured to them. Suitable screen

moulding or the like 37 is shown holding the wire in place.

The lower edge of each of the rails 23, 25 and 26 is provided with a central longitudinal groove 38 and with a central notch or socket 39. The upper edge of each of the rails 25, 26 and 19 is provided with a central longitudinal ridge 40, the central portion of which is removed at 41. Central removable posts 42 lie against the inner sides of the fixed posts 31, 32 and 33 and have their upper ends seated in the notches or sockets 39, said removable posts 42 resting on the adjacent rails 25, 26 and 19 where the ridges 40 are cut away, at 41. These removable posts 42 have vertical grooves 43; the upper ends of these grooves communicate with the grooves 38; and the lower ends of said grooves receive the ridges 40. The posts 42 are thus normally held in place but sufficient space is provided over each post to allow it to be lifted from engagement with the ridge 40, permitting easy removal of the post. To aid, the upper outer corner of each post 42 is preferably rounded off as shown at 44.

Closures are slidably engaged with the various rails and extend slidably through the slots 45 between the stop strips 34 and 35. Each of these closures preferably consists of a glass pane 46 having a grooved shoe 47 on its lower edge. The upper edge of each pane 46 fits slidably in one of the grooves 38, the grooved shoe 47 engages one of the ridges 40, and the inner end of each pane is receivable in one of the grooves 43. A weather strip 48 (Fig. 4) may be provided in the inner edge of each stop strip 34 and a weather seal 49 may be secured to the outer end of each shoe 47 to prevent entrance of rain and cold air through the slots 45. Also, if desired, the grooves 38 and 43 could well be lined with felt or the like. The strip 48 not only forms a weather seal but each time the pane 46 is opened or closed, said pane is wiped by said strip, tending to keep the pane clean.

When any one of the removable posts 42 is removed, either of the pans 46 cooperable with it may be slid inwardly sufficiently to clear the slot 45, whereupon said pane may be lifted to free the shoe 47 from engagement with the ridge 40. Then, the pane may be tilted to an inclined position and removed, for cleaning or to permit replacing of a damaged pane. It will also be clear that all of the panes may be left out of the frame until the building is about completed, and that they may then be easily installed.

The frame structure of the window constitutes a single unit around which the wall 20 is built, with the projecting ends of the rails 23, 25, 26 and 19 lying against the inner side of said wall. These rails are of substantially the same thickness as the conventional furring strips 50 and will thus effectively aid in forming pockets between the wall 20 and the inner wall 51 when the latter is secured to said furring strips. Into these pockets, the panes or closures are slidable. The inner wall 51 may abut and be flush with the inner crown bar 16 and the inner stiles 18, and suitable trim moulding 52 may be secured to said parts 16 and 18. The wall 51 may also abut the lower side of the inner sill 14 to which trim moulding 53 may be secured.

From the foregoing, it will be seen that a novel and desirable window construction has been provided, and while preferences have been disclosed, attention is again invited to the possibility of making variations within the scope of the invention as claimed. Suitably located nails have been

illustrated for securing the various frame parts together but other adequate fastening means could of course be employed. Moreover, it is of course possible to construct the frame in such a way that fasteners such as nails will not be necessary.

I claim:

1. In a window, a frame having opposed side members, an upper and a lower rail extending from one of said side members to the other, said side members each having a vertical slot through which said rails extend, the lower edge of said upper rail being formed with a longitudinal groove and with a downwardly open socket, the latter being disposed centrally between the ends of said upper rail, the upper edge of said lower rail being formed with a longitudinal ridge the central portion of which is removed under said socket, a central post resting on the central portion of said lower rail and having its upper end seated in and upwardly slidably in said socket of said upper rail, said post having vertical grooves which communicate at their upper ends with said groove of said upper rail, said ridge of said lower rail being seated in the lower ends of said vertical grooves of said post, two closures extending slidably through the aforesaid slots respectively and having their upper edges slidably received in the groove of said upper rail, the lower edges of said closures having grooves slidably engaging said ridge of said lower rail, the inner ends of said closures being receivable in said grooves of said post when said closures are slid to closed position; said post being upwardly disengageable from said ridge of said lower rail, to permit post removal, when said closures are slid from the grooves of said post; said closures being upwardly disengageable from said ridge of said lower track to permit closure removal when said closures are slid from said slots after removal of said post.

2. In a window, a fixed upper closure-guiding rail having a downwardly open socket between its ends, a fixed lower closure-guiding rail, said lower rail having a longitudinal ridge a portion of which is removed under said socket, and a closure-abutting post resting on said lower rail and having its upper end seated in and upwardly slidably in said socket, said post having vertical closure-engaging grooves the lower ends of which receive said ridge of said lower rail, said post being upwardly shiftable from said ridge to permit post removal.

3. In a window, a frame having opposed side members, an upper and a lower rail extending from one of said side members to the other, at least one of said side members having a vertical slot through which said rails extend, the lower edge of said upper rail being formed with a longitudinal groove and with a downwardly open socket, the upper edge of said lower rail being formed with a longitudinal ridge a portion of which is removed under said socket, a post resting on the portion of said lower rail from which said ridge is removed, said post having its upper end seated in and upwardly slidably in said socket of said upper rail, said post having a vertical groove which communicates at its upper end with said groove of said upper rail, said ridge of said lower rail being seated in the lower end of said vertical groove of said post, a closure extending slidably through the aforesaid slot and having its upper edge slidably received in the groove of said upper rail, the lower edge of said closure having a groove slidably engaging said ridge of said lower rail, one end of said

closure being receivable in said groove of said post when said closure is slid to closed position; said post being upwardly disengageable from said ridge of said lower rail, to permit post removal, when said closure is slid from the groove of said post; said closure being upwardly disengageable from said ridge of said lower track to permit closure removal when said closure is slid from said slot after removal of said post.

4. In a window, a fixed upper closure-guiding rail having a downwardly open socket, a fixed lower closure-guiding rail, said lower rail having a longitudinal ridge a portion of which is removed under said socket, and a closure-abutting post resting on the portion of said lower rail from which said ridge is removed, said post having its upper end seated in and upwardly slidable in said socket, said post having a vertical closure-engaging groove the lower end of which receives said ridge of said lower rail, said post being upwardly shiftable from said ridge to permit post removal.

5. In a window, a frame having a stile, upper and lower horizontal rails secured to said stile, a horizontally slidable closure engaged with said rails for removal by successive lifting, lateral swinging and lowering operations, said stile having a vertical slot through which said closure is slid, a vertical post extending from one of said rails to the other and spaced from said stile, said post occupying a position to abut one end of said closure and stop the closing movement of said closure while the other end of said closure is still within said slot, thereby normally preventing performance of the aforesaid closure removal operations, said post having a seat substantially throughout its length to receive said one end of said closure, said upper rail having a downwardly open socket so receiving the upper end of said post that the post may be lifted and its lower end swung laterally to clear said lower rail, and coacting connecting means on said lower rail and the lower end of said post, said connecting means being disengageable from each other by lifting said post; whereby said post may be readily removed to permit sliding of said closure from said slot, thereby permitting performance of the aforesaid closure removal operations.

6. In a window, a frame having right and left stiles, upper and lower horizontal rails extending between and secured to said stiles, right and left horizontally slidable closures engaged with said rails for removal by successive lifting, lateral swinging and lowering operations, said stiles having vertical slots through which said closures are slidable respectively, a central, rigid, one-piece, vertical post extending from one of said rails to the other and having seats substantially throughout its length to receive the inner ends of said closures, said post normally prohibiting inward sliding of said closures entirely from said slots and thereby prohibiting performance of the aforesaid closure removal operations, and means on said frame for engaging the upper and lower ends of said post for securing it in its central position and permitting it to be quickly detached as a unit when said closure is to be removed; whereby upon removal of said post, either closure may be inwardly slid from its respective slot and said closure removal operations may be performed.

7. In a window, a frame having right and left stiles, upper and lower horizontal rails extending between and secured to said stiles, right and left horizontally slidable closures engaged with said rails for removal by successive lifting, lateral swinging and lowering operations, said stiles having vertical slots through which said closures are slidable respectively, a central vertical post extending from one of said rails to the other and having seats substantially throughout its length to receive the inner ends of said closures, said post normally prohibiting inward sliding of said closures entirely from said slots and thereby prohibiting performance of the aforesaid closure removal operations, said upper rail having a downwardly open socket so receiving the upper end of said post that the post may be lifted and its lower end swung laterally to clear said lower rail, and coacting connecting means on said lower rail and the lower end of said post, said connecting means being disengageable from each other by lifting said post; whereby said post may be readily removed to permit sliding of either closure from its respective slot, thereby permitting performance of the aforesaid closure removal operations.
8. In a window, a frame having a stile, upper and lower horizontal rails secured to said stile, a horizontally slidable closure engaged with said rails for removal by successive lifting, lateral swinging and lowering operations, said stile having a vertical slot through which said closure is slid, a rigid, one-piece vertical post extending from one of said rails to the other and detachable as a unit from said frame, said post being spaced from said stile and occupying a position to abut one end of said closure and stop the closing movement of said closure while the other end of said closure is still within said slot, thereby normally preventing performance of the aforesaid closure removal operations, said post having a seat substantially throughout its length to receive one end of said closure, and means on said frame for engaging the upper and lower ends of said post for securing it in said position and permitting it to be quickly detached as a unit when said closure is to be removed; whereby upon removal of said post, said closure may be slid entirely from said slot and said closure removal operation may be performed.

FRANK McM. SAWYER.
